Attorney.

UNITED STATES PATENT OFFICE.

GRACE PRICE, OF MOUNT AIRY, VIRGINIA.

CONTAINER.

Application filed March 27, 1923. Serial No. 628,084.

To all whom it may concern:

Be it known that I, GRACE PRICE, a citizen of the United States, residing at Mount Airy, in the county of Pittsylvania and 5 State of Virginia, have invented a new and useful Container, of which the following is a specification.

This invention is a shipping receptacle in which to ship parcel post, express and 10 similar matter.

One of the objects of the invention is to provide a container designed particularly for shipment of dairy products, so constructed that the contents may be conveniently packed and unpacked. A further 15 object is to provide a device in which butter may be shipped in packages of desirable size, and in which waste and the labor of packing is practically prevented. A further 20 object is to provide means by which butter packages may be readily lifted out of the container, and at the same time be adequately protected from contamination in handling. A further object is to provide 25 a container of the character mentioned, constructed of separable parts, and means for firmly uniting the parts against accidental separation.

The invention will be hereinafter fully 30 set forth and particularly pointed out in the claims.

In the accompanying drawings:—

Figure 1 is a side elevation illustrating a container constructed in accordance with 35 the invention. Figure 2 is a vertical sectional view illustrating the container packed with butter. Figure 3 is a similar view showing the container packed with both eggs and butter. Figure 4 is a detail perspective view illustrating the butter package. Figure 5 is a detail view illustrating the connection between the fabric wrapper and the butter-supporting disk.

Referring to the drawing, the container 45 which is of approximate barrel-shape comprises two sections 10 and 11, suitably braced by hoops 12, and 12^a. Each section is formed with a head 13 and flares outwardly to an open end 14. The open ends 50 of both sections 10 and 11 are provided with complementary interengaging portions 15, of any desired construction, for separably uniting the sections, screw threads being illustrated for this purpose.

For convenient handling of butter and the like, a plurality of circular supporting-disks 16, of a diameter corresponding to the interior diameter of the section within which it is located, are employed, each disk having secured thereto a woven fabric 17, which is designed to enclose the 60 contents of the package. The fabric may be secured to the disk in any desired manner. As shown, the disk is provided with a peripheral groove 18, in which the fabric 65 is secured by means of a cord or the like 19, thereby giving the fabric an approximate tubular shape. If desired, the surface of the disk 16 which comes in contact with the butter, may be shaped to provide 70 a suitable printing mold for the butter, as indicated at 20.

In practice, a disk 16, and the fabric 17, are moistened with cold water. The disk is then placed upon the head or bottom of a 75 container section, with the fabric lining or wrapper lying contiguous to the wall of the section. Butter or other material is then packed within the space surrounded by the fabric 17, and upon the exposed surface of the disk 16, in much the same manner as one would fill an ordinary butter mold. When the desired quantity of material has been packed, for example enough to make a 80 pound package, the free end portions of the fabric lining 17, are folded down so as to fit over and cover the exposed surface of the material, thereby completely enclosing the package. A second disk 16 is then placed upon the finished package and the 85 same process repeated. In the construction shown each section 10 and 11 is of a size to contain two packages of uniform weight.

After the butter has been packed in both 90 sections, the open ends of the sections are brought together and united by the screw threads 15, and the package is ready to ship.

The sections may be locked against accidental disengagement in any desired manner. In the drawings is shown an address tag 22, of a size to fit within the space between the contiguous hoops 12, said address tag having means for separably engaging suitable securing devices carried by the respective sections 10 and 11. The securing devices for the address tag are of such a nature that the tag will not become accidental-

ly disengaged, and yet it may be readily separated from the container when it is desired to gain access to the contents thereof.

When it is desired to unpack the contents 5 of the receptacle, the sections 10 and 11 are disengaged in a manner which will be readily understood from the drawing, and placed upon a table or other support, resting upon the heads 13. The operator then grasps the 10 folded over ends 21, of the tubular fabric 17, and lifts out the topmost package intact. The other packages may be successively removed in the same way. The covering ends of the fabric are then moved back and the exposed 15 flat surface of the package may be placed upon a plate or the like, and the circular disk subsequently lifted, leaving the package intact upon the plate, with or without the ornamental print, according to whether or not 20 the disk is provided with the ornamental surface 20.

By employing the fabric lining, it is possible to lift the package out intact, and the fabric may be unwrapped from the contents 25 of the package without adhering thereto, it being an inherent characteristic of the fabric that when moist it will not adhere to butter or the like. If the butter should be soft at the time that it is desired to unpack it, the container sections may be separated and temporarily placed in a refrigerator, or other cold place until the butter is sufficiently hard to handle.

If desired, jams, jelly, preserves and the 30 like, may be packed and shipped in a similar manner, provided they are placed within the package formed by the disk 16 and fabric 17, before congealing.

If desired the container may be made to 35 serve the purpose of shipping eggs as illustrated in Figure 3. Referring to said figure, one of the sections is shown as provided with corrugated partitions 25 of a well-known type, dividing the section into cells. Thus, 40 it is possible to ship both eggs and butter in varying quantities. For instance, the eggs are packed in layers of four each, so that the container illustrated may easily be employed for shipping one pound of butter and one 45 dozen eggs, or the relative quantities may be varied as desired.

The advantages of the invention will be 50 readily apparent to those skilled in the art to which it appertains. By employing a container constructed of two separable parts which may be readily united, a receptacle is 55 provided which may be conveniently packed and unpacked. The fabric lining is of particular advantage in that it eliminates a great deal of the labor in handling, as well as 60 the waste of butter, or other material, because it serves to prevent the material from adhering to the walls of the container. It also permits the material to be removed from 65 the container in uniform masses of predeter-

mined size, and avoids the necessity of removing it in unsightly hunks, or the necessity of using a spoon if the material is soft. It also solves a way of lifting the package 70 of butter out of the container, as well as providing a means for insuring complete separation and non-adherence of the superposed packages.

By employing the address tag for preventing relative rotation of the sections 10 75 and 11, a simple device is provided for preventing accidental separation of the sections. At the same time, it serves the additional function of providing suitable means for the address to which the container is to be 80 shipped.

Having thus explained the nature of the invention and described an operative manner of constructing and using the same, although without attempting to set forth 85 all of the forms in which it may be made, or all of the forms of its use, what is claimed is:—

1. A container of the character described comprising a receptacle section, a removable disk corresponding to the internal diameter of said section, and a fabric wrapper attached at one end to said disk and having a free portion foldable over material placed upon said disk. 90

2. A container of the character described comprising a receptacle section, a removable circular disk corresponding to the internal diameter of said section, and a fabric secured to said disk in a manner to cause 100 it to assume a tubular form and positioned to lie between the wall of the receptacle and material placed upon the disk, the free end of the fabric being foldable over said material. 105

3. A container of the character described comprising a receptacle section, a circular disk of a diameter corresponding to the internal diameter of the receptacle, said disk having a peripheral groove, a fabric lining, 110 and means for securing one end of said lining in the peripheral groove of said disk, whereby the fabric will lie between the wall of the receptacle and material placed on the disk, the free end of the fabric being 115 foldable over said material.

4. A container of the character described comprising a receptacle section, a circular disk of a diameter corresponding to the diameter of said receptacle, and a fabric 120 having one end secured to the periphery of the disk, whereby the fabric will lie between the wall of the receptacle section and the material placed on the disk, the other end of the fabric being free and foldable 125 over the material.

5. A container of the character described comprising a receptacle section having a head, and an open portion, said section flaring outwardly from said head to said 130

- open portion, a removable disk of a diameter corresponding to the internal diameter of said section, a fabric wrapper secured to said disk and positioned to be interposed 5 between the wall of the receptacle section and the material placed upon said disk, and means for closing the open portion of said receptacle section.
6. A container of the character described 10 comprising two receptacle sections each open at one end, means for separably uniting the open ends, removable disks corresponding to the internal diameters of the respective receptacle sections, and fabric linings secured 15 to the respective disks and positioned to lie between the material placed upon a disk and the wall of the receptacle section in which said disk is located.
7. A container of the character described 20 comprising two flaring receptacle sections each having a head, and an open end, the larger diameter of each section being at the open end, means for separably uniting the open ends of the receptacles, removable 25 disks in the respective receptacles, said disks being of a diameter corresponding to the internal diameter of the receptacle sections, and fabric wrappers attached to the respective disks.
- 30 8. A container of the character described comprising two receptacle sections each having a closed head and an open end, said open ends being provided with complementary threaded portions whereby the said sections 35 may be separably engaged, removable disks within the respective receptacle sections, said disks being of a diameter corresponding to the internal diameters of said receptacle sections, and fabric wrap- 40 pers secured to the respective disks.
9. A container of the character described comprising two receptacle sections each open at one end, means for separably uniting the open ends, removable disks corresponding to the internal diameters of the respective 45 receptacle sections, fabric linings secured to the respective disks and positioned to lie between the material placed upon a disk and the wall of the receptacle section in which said disk is located, and an address 50 tag separably attached to both receptacle sections and serving to limit relative movement of said sections.
10. A container of the character described 55 comprising two receptacle sections each having a closed head and an open end, said open ends being provided with complementary threaded portions whereby the said sections may be separably engaged, removable disks within the respective receptacle sections, said disks being of a diameter corresponding to the internal diameters of said receptacle sections, fabric wrappers secured to the respective disks, and an address tag 60 separably attached to both receptacle sections and serving to limit relative movement of said sections.
11. A container of the character described 65 comprising two receptacle sections each open at one end, means for separably uniting the open ends, removable disks corresponding to the internal diameters of the respective receptacle sections, fabric linings secured to the respective disks and positioned to lie between the material placed upon a 70 disk and the wall of the receptacle section in which said disk is located, an address tag, and complementary separable fastening means attached to said address tag and to said receptacle sections.
- In testimony whereof I have hereunto set my hand.

GRACE PRICE.
